CLAIM

The ornamental design for a light ring for shaver, as shown and described.

DESCRIPTION

FIG. 1 is a perspective view showing the first embodiment of a light ring for shaver;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a perspective view showing the second embodiment of a light ring for shaver;

FIG. 9 is a front elevational view thereof;

FIG. 10 is a rear elevational view thereof;

FIG. 11 is a right side elevational view thereof;

FIG. 12 is a left side elevational view thereof;

FIG. 13 is a top plan view thereof; and,

FIG. 14 is a bottom plan view thereof.

The broken lines illustrate the environment for the light ring for shaver and form no part of the claimed design.

The shading on the claimed design illustrates color contrast.
